UNITED STATES PATENT OFFICE.

FREDERICK AUGUSTUS PURCHAS, OF McGRAW, NEW YORK.

DESIGN FOR A BOX.

Application filed July 7, 1926. Serial No. 18,271. Term of patent 14 years.

To all whom it may concern:

Be it known that I, FREDERICK A. PURCHAS, a citizen of the United States, and a resident of McGraw, in the county of Cortland and State of New York, have invented a new, original, and ornamental Design for Boxes, of which the following is a specification, reference being had to the accompanying drawing, forming part thereof.

I claim:

The ornamental design for a box, as shown.

FREDERICK AUGUSTUS PURCHAS.
